SPARK PLUG PUMP

Sigmund E. Edelstone, Chicago, and Albert L. Jenks, Dixon, Ill., assignors to Dupli-Color Products Company, Inc., Chicago, Ill., a corporation of Illinois

Application March 11, 1950, Serial No. 8,484

Term of patent 7 years

(Cl. D14—6)

To all whom it may concern:

Be it known that we, Sigmund E. Edelstone and Albert L. Jenks, citizens of the United States, residing, respectively, at Chicago, in the county of Cook and State of Illinois, and Dixon, county of Lee, and State of Illinois, have invented a new, original, and ornamental Design for Spark Plug Pump, of which the following is a specification, reference being had to the accompanying drawing forming a part thereof, in which

Figure 1 is a perspective view of a spark plug pump embodying our new design;

Figure 2 is a side elevation thereof;

Figure 3 is also a side elevation thereof but at right angles to the view of Fig. 2;

Figure 4 is a top plan view of the said pump; and

Figure 5 is a bottom plan view thereof.

We claim:

The ornamental design for a spark plug pump, substantially as shown and described.

SIGMUND E. EDELSTONE.

ALBERT L. JENKS.
